UNITED STATES PATENT OFFICE.

WILLIAM E. LUNDGREN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-THREADER BLOCK.

Application filed January 30, 1925. Serial No. 5,839.

This invention relates to self-threading shuttle blocks and it is the principal object of the invention to provide a shuttle threader block which will effectively prevent mis-threading by the use of a pair of normally contacting yielding tongues between which the yarn passes when the eye is being threaded.

A further object of the invention is to provide a shuttle threader block having portions thereof formed of resilient material which may be bent by the operator to effect slight adjustments.

A still further object of my invention is to provide a shuttle threader block element of such design that the same may be employed either on right or left hand shuttles.

With these and other objects in view which will appear as the description proceeds, my invention resides in the combination and arrangement of parts hereinafter described and set forth in the claims.

In the accompanying drawings wherein I have shown one form of my invention,

Fig. 1 is a top plan view of one end of a shuttle having my invention applied thereto,

Fig. 2 is a front elevation of the shuttle looking in the direction of arrow 2, Fig. 1,

Fig. 3 is a vertical section on line 3—3 of Fig. 1,

Fig. 4 is a vertical section on line 4—4 of Fig. 1,

Fig. 5 is a horizontal section on line 5—5 of Fig. 1, and

Fig. 6 is a perspective view of the element forming an important part of my invention.

Referring more particularly to the drawings it will be seen that I have provided a shuttle 10 suitably formed to hold a bobbin 11 and having therein a vertical slot 12 through which the bobbin passes at the time of replenishing.

The eye end of the shuttle is provided with a slot 13 which receives the vertical walls 14 and 15 respectively of the block 16, said walls defining a thread passage 17. As shown in Fig. 4 there is extending from wall 15 across the passage 17 a hooked extension 18 so disposed as to catch the thread as the latter is unwound from the bobbin 11. A felt pad 19 may be secured in any approved manner in block 16 and serves with the hook

18 to define an entrance to the passage 17. A foot 20 indicated in dotted lines in Fig. 2, 55 depends from the block 16 and has extending therethrough a bolt 21 by means of which the block is held securely to the shuttle.

In carrying out my invention I form the lower portion of the block 16 with a substantially horizontal surface 30 to which is secured the bottom wall 31 of a retainer 32. As shown in Fig. 6 the retainer is formed of a single piece of sheet material, preferably resilient, and has side walls 33 terminating 65 in resilient downwardly inclined pointed tongues 34 which extend from the opposite walls 33 and are held in light yielding contact with each other so as to permit passage of yarn therethrough. The tongues are 70 pointed downwardly as indicated in Fig. 3 and being in contact serve to close the passage 17 to prevent the yarn from "ballooning" out of said passage.

As shown in Fig. 1 the wooden part of the 75 shuttle is provided with a laterally extending opening 35 through which the yarn may extend and is further provided with a sloping channel 36 extending substantially in alignment with the passage 17. The tongues 80 34 terminate at a point somewhat above the bottom of the channel 36 as shown in Fig. 2. In order to hold the retainer in place the same may be secured by means of screw 38 which is threaded into the bottom of the 85 block 16. As shown more particularly in Figs. 1, 5, and 6 each tongue has extending therefrom a guard 39 formed with a notch 40 which will receive the yarn should it fail to be properly threaded.

In operation, when a fresh bobbin has been put in the shuttle by the replenishing mechanism (not shown) the thread thereon which extends to the thread holder will lie above the passage 17. As the shuttle is picked out 95 of the box the yarn will unwind in such a direction as will cause the same to pass down the narrow space defined between the hooked extension 18 and the adjacent wall 14 of the shuttle block. As the shuttle continues its 100 flight across the loom the weft, indicated at W, will be drawn downwardly between the resilient tongues 34, this action being possible because the channel extends under the tongues. On the return flight the weft is 105 drawn into passage 35 and the block is com-

pletely threaded, but should the thread fail to enter passage 35 it will fall into one or the other of the notches 40.

The guard adjacent the passage 35 lies 5 high enough above the wooden portion of the shuttle thereunder to permit the yarn W to enter said passage 35 and the other guard extends beyond the rear wall 41 of channel 36 to prevent the yarn from passing around the 10 guard. Also, the rear guard is preferably somewhat lower than the adjacent wooden portion of the shuttle.

From the foregoing it will be seen that the threader block set forth herein is so constructed 15 that it cannot be unthreaded after the yarn passes downwardly between the tongues, even though the shuttle may remain inactive on the opposite side of the loom for a number of picks. It will further 20 be noted that because of the construction of the retainer element the tongues thereof may be bent to the desired adjustment and it will be noted further that the tongues are disposed symmetrically about the axis of 25 the passage 17 so that the thread may be drawn either to the right or to the left, making the element usable on either a right or left hand loom.

Having thus described my invention it 30 will be apparent that changes and modifications may be made therein by those skilled in the art without departing from the spirit and scope of the invention and I do not wish to be limited to the details 35 herein disclosed, but what I claim is:

1. In a self threading shuttle having a thread passage therethrough, a block having bottom and side walls, a thread retainer forming part of the thread passage and 40 having a pair of similarly formed resilient tongues extending downwardly and in the direction in which the weft is drawn through the passage, one tongue extending from each of the side walls of the block, the tip ends 45 of said tongues being normally in contact to close the top side of the thread passage and yieldable to allow the weft to pass therebetween.

2. In a self threading shuttle, a block 50 having side and bottom walls defining a thread passage, a thread retainer associated with the block, and resilient downwardly extending pointed tongues carried by the retainer for the upper portion of the thread 55 passage, said tongues extending in a direction substantially parallel to the thread as the latter passes through the passage and being normally in contact with each other and yieldable to permit yarn to pass there- 60 between.

3. In a self threading shuttle having a thread passage therethrough, a retainer for the thread, and similarly formed normally 65 contacting yieldable downwardly extending tongues extending from opposite sides of

the passage and normally closing the top of said passage, and extending in the direction in which the thread is drawn through the passage.

4. In a self threading shuttle having a 70 thread passage therein, a thread retainer encircling the passage and having a pair of normally contacting downwardly extending tongues at least one of which is yieldable, said shuttle being formed with a groove 75 located under the tongues, said tongues extending above the bottom of the groove and in the same direction in which the thread is drawn through the passage.

5. In a self threading shuttle having a 80 thread passage therein, a thread retainer located in the passage, downwardly extending resilient normally contacting tongues formed with the retainer to close the upper 85 side of the thread passage, and extending in the direction in which the thread is drawn through the passage, and thread guards formed on said retainer, one guard being adjacent each tongue and defining therewith a notch to receive the thread. 90

6. In a self threading shuttle, a block having side and bottom walls to define three 95 sides of a thread passage, a thread retainer secured to the bottom wall of the block and extending along the side walls, and normally contacting downwardly extending tongues lying in the same direction as that in which the thread is drawn through the passage formed on the upper part of the retainer, the tongues extending toward each other 100 from the opposite sides of said retainer to close the thread passage, at least one of said tongues being yieldable and movable from the other tongue to define a passage for thread. 105

7. A thread retainer for a self threading shuttle having a thread passage therethrough and comprising bottom and side walls and having the upper portion thereof formed with a pair of normally contacting 110 downwardly extending tongues lying in the same direction as that in which the thread is drawn through the passage at least one of which tongues is resilient with respect to the other. 115

8. In a self threading shuttle, a block having substantially vertical walls located in the shuttle and having extending therethrough a thread passage, a thread retainer associated with the block, resilient normally 120 contacting tongues extending from opposite sides of the retainer to close the upper portion of the thread passage and guards associated with each tongue, said guards defining a notch with the tongue, the shuttle 125 being provided with an outlet communicating with the thread passage, the notches being positioned to receive the thread should the latter fail to enter the outlet. 130

9. In a self threading shuttle having a 135

thread passage therein, a thread retainer having yieldable normally contacting downwardly extending tongues to close the upper portion of the thread passage, the shuttle being provided with a channel extending substantially in alignment with the thread passage under the tongues, and a guard formed on one of the tongues and extending beyond the rear wall of the channel to define with the tongue a thread receiving notch.

In testimony whereof I have hereunto affixed my signature.

WILLIAM E. LUNDGREN.
